Primary Examiner—Alan P. Douglas*Assistant Examiner*—R. Spear*Attorney, Agent, or Firm*—Hugh E. Smith[57] **CLAIM**

The ornamental design for a spray can extender, as shown and described.

DESCRIPTION

FIG. 1 is a front elevational view of the spray can extender showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view thereof, showing my new design in its full length.

The broken line showing of a spray can is for illustrative purposes only and forms no part of the claimed design.

FIG. 1

FIG. 2
